UNITED STATES PATENT OFFICE

KNOWLES YOUNGBLOOD, OF NASHUA, NEW HAMPSHIRE, ASSIGNOR TO NASHUA-YOUNGBLOOD COMPANY, OF NASHUA, NEW HAMPSHIRE, A CORPORATION OF MASSACHUSETTS

MACHINE FOR MAKING WRAPPING BANDS

Application filed November 8, 1927. Serial No. 231,902.

This invention relates to the production of paper bands having their end portions provided with adhesive material such as disclosed in Letters Patent No. 1,589,503 issued ⁵ to me June 22, 1926.

Bands of the type referred to are useful for many purposes such as the wrapping of laundry articles or the wrapping of packages of money. If the adhesive coated ends ¹⁰ of the bands curl it is frequently difficult to properly moisten the adhesive coating and to affix it properly to the portion of the band on which it is laid. As is well known, when adhesive is applied to paper and dried the ¹⁵ contraction of the gum, when drying, curls up the paper.

One of the objects of my invention is to provide bands of the character referred to with tabs having a minimum tendency to curl.

Another object is to provide bands of the type illustrated in said patent with accurately connected and located tabs.

With the above mentioned objects in view ²⁵ the invention consists in the method and machine substantially as hereinafter described and claimed.

Of the accompanying drawings:

Figure 1 is a side elevation, partly in section, of the essential portions of the machine by which my invention is practiced.

Figure 2 is a plan view of the parts shown in the middle portion of Fig. 1, on a smaller scale.

Figure 3 is a detail view looking in direction of arrow 3 in Fig. 1.

Figure 4 is a detail elevation of the support for the gummed strip.

Figure 5 is a plan view of the moistening device illustrated in Fig. 1 but on a larger scale.

Figure 6 represents a section on line 6-6 of Fig. 5.

Figures 7 and 8 are plan views of the two plates at the top of the moistening reservoir.

Figures 9 and 10 represent sections on line 9-9 and 10-10 of Figs. 7 and 8, respectively.

Figure 11 is a plan view of one of the completed bands made according to my invention.

Similar reference characters indicate similar parts or features in all of the views.

Referring first to Fig. 1 a suitable frame work 12 is provided, said frame work supporting a shelf or bracket 13 and supporting a shaft 14 for a roll of paper web material *a*. Also supported by the frame work are guide rolls 15-16, a guide roll 17, a suitably driven roll 18, and an idly rotating pressure or pinch roll 19.

Supported by the bracket 13 is a stand 20 having a pin 21 for a roll of a gummed strip *b*, a suitable friction strip 22 being also mounted on the pin 21.

Supported by the bracket 13 is the base 23 of the moistening device, the latter including a water chamber 24 (Figs. 1 and 6) to which water is supplied by a pipe 25 from a suitable reservoir or other source of supply 26.

Mounted on the walls of the water chamber ²⁷ 24 are two plates between which the strip *b* is drawn as hereinafter described. The upper plate 27 has a wide slot 28 through which a wick 29 in the water chamber projects. The strip *b* passes under a roll 30, over a roll ³¹ 31 and under a roll 32 having annular guide ribs 33 properly spaced as indicated in Fig. 5, said roll 32 being supported by arms 34.

Referring again to Fig. 1 vertical guides ³⁵ are provided in which is mounted a shaft ³⁶ 36 having a pressure roll 37 the purpose of which will presently be explained. Said shaft 36 is free to descend by gravity.

The lower plate 27 on the water chamber, and over which the strip *b* is drawn, has a ³⁸ lip 38 which serves to steady the upper portion of the wick 29, and to also deflect or direct any surplus water that might be drawn along by the strip *b* back into the water chamber. The said plate 39 has a curved rear edge ⁴⁰ 40 and is slotted to provide an opening 41 (Fig. 7). It also has a surface rib 42 which serves to guide the strip *b* so that only the portion of said strip, which is to overlap and be connected to the web *a*, will be moistened, as indicated by comparing Figs. 2 and 3.

It is important that the gummed strip *b* shall have no tendency to curl. Therefore, it has its coating broken as explained in Letters Patent 1,368,080 to Van Sluys, issued Febru- ⁴³ 1921.

ary 8, 1921. Usually the machine as illustrated in that patent treats a wide gummed web which is afterward cut into narrow strips. It is such a strip as this which is employed in carrying out my invention.

5 In operation a roll of the strip *b*, carried by the stand 20, is threaded through the moistening device as illustrated by Figs. 1 and 6 and is adhesively attached to the surface margin of the roll or web of paper *a* and the two strips or webs *a* and *b* are then drawn in the direction indicated by the arrows in Fig. 1, such drawing being mainly effected by the rolls 18-19. As has been 10 mentioned, the cover plates of the moistening device guide the strip *b* in such manner relatively to the mounting of the web roll *a* that the strip *b* does not overlay its full width on the web *a* but only a marginal portion 15 thereof as illustrated by Figs. 2 and 3, and it is only this lateral portion of the strip *b* which is to overlap the margin of the web *a*, that passes in contact with the moistening wick 29. This is to prevent the softening of 20 the gum which is on that portion of the strip *b* which projects beyond the margin of the web *a* from being moistened so as to consequently require somewhat prolonged drying. The pressure roll 37 is of a width to press the 25 moistened margin of the strip *b* on to the margin of the web *a* and such connection does not require much time for drying before the combined web *a* and strip *b* are transversely cut to produce such articles as illustrated by 30 Fig. 11.

35 In view of the fact that any suitable cutting mechanism may be employed, it is not necessary to illustrate the same. In fact the transverse cutting might be effected by manu- 40 ally operated shears. Furthermore, the method of producing the articles such as illustrated by Fig. 11 might be entirely carried out or practiced manually.

Fig. 1 illustrates that the united or com- 45 bined strip *b* and web *a* travel for a consider- able distance, after leaving the point of pressure together by the roll 37, about the rolls 15-16 and to the drawing rolls 18-19. This provides ample space for the location 50 of the moistener device and also gives ample time for the adhesively secured margin of the strip and web to dry before being trans- versely cut.

55 While I have illustrated a strip *b* as connected to only one margin of the web *a*, it is obvious that a duplicate mechanism could be employed to connect a similar strip to the other margin of the web so that the web 60 would have strips *b* attached to and project- ing from each edge thereof. When such duplicate mechanism is employed the web *a* is to be longitudinally severed approximately its mid-width so that each transverse cut- 65 ting of the web and bands would produce

two of the wrapping bands illustrated by Fig. 11.

Having now described my invention, I claim:—

1. A machine for adhesively uniting two 70 strips of paper in marginal overlapping relationship one of which strips has an adhesive coating, comprising means for causing the strips to travel from two sources of supply, means for moistening a limited lateral portion of the coated strip, and means for pressing the two strips together. 75

2. A machine of the character described, having means for feeding a web of paper, means for guiding a gummed strip to position on a marginal portion of said web, means for applying moisture to the gummed strip before its contact with said web, and means for simultaneously severing the web and strip transversely. 80

3. A machine of the character described, having a support for a web of paper, means for guiding a gummed strip to position overlapping and projecting from a margin of said web, means for moistening that portion of the gummed strip which is to overlap said web, and means for pressing together the overlapping portions of the web and strip. 85

4. A machine for uniting two lengths of paper to prepare them for transverse cutting 90 into duplex sections, said machine including means for applying a narrow strip of gummed paper to the marginal portion of a traveling wide strip of paper, means for applying moisture to one of the strips to effect adhesive uniting of the strips, and means for pressing said strips together. 95

In testimony whereof I have affixed my signature.
